UNITED STATES PATENT OFFICE.

JOHN D. STEWART, OF GLENWOODVILLE, ALBERTA, CANADA.

DISK-SHARPENER.

1,084,500.

Specification of Letters Patent.

Patented Jan. 13, 1914.

Application filed August 16, 1913. Serial No. 785,169.

To all whom it may concern:

Be it known that I, JOHN D. STEWART, a citizen of Canada, residing at Glenwoodville, in the Province of Alberta and Dominion of Canada, have invented new and useful Improvements in Disk-Sharpener, of which the following is a specification.

This invention is an improved disk sharpener especially adapted for grinding harrow and plow disks and other like devices, the object of the invention being to provide an improved machine of this character which automatically turns the disk while the machine is in operation so as to present all portions of the periphery of the disk successively to the action of the grinding stone, another object being to simplify the construction of the machine.

With the above and other objects in view, the invention consists in the construction, combination and arrangement of devices hereinafter described and claimed.

In the accompanying drawings:—Figure 1 is a front elevation of a disk sharpener constructed in accordance with my invention, showing the same arranged for operation on a harrow disk. Fig. 2 is a side elevation of the same. Fig. 3 is a vertical longitudinal sectional view of the same. Fig. 4 is a detail plan of the boxing, the supporting arm therefor, the driving shaft and one of the work revolving gears, and showing the vertical work carrying shaft in section. Fig. 5 is a similar view of the supporting bracket of the roller and its connections, showing the post in horizontal cross section and also showing the arm which carries said roller in cross section.

My improved disk sharpener is here shown as having a suitable supporting base 1 and a standard 2. A horizontally arranged arm 3 is at the upper end of the standard and extends from the rear side thereof. A cross bar 4 is directly at the upper end of the standard and is arranged at right angles to the bar or arm 3. A vertically arranged casing 5 comprises a body 6 open at its front side and a cover 7 to close the front side of the body.

The lower end of the body of the casing is secured to the front side of the standard 2 at the upper end thereof so that the said body of the casing rises from said standard and in the upper portion of the body of the casing is a bearing 8 for a short shaft 9 which is provided at its rear end with a

grind stone or disk 10 which, in practice, is preferably made of carborundum but which may be made of any suitable material and may be of any suitable size. On the front end of the said shaft is a spur gear 11. An axle 12 of a small gear 13 and a large gear 14 has its bearings in the body and cover of the casing. The gear 14 engages the gear 11 and the gear 13 engages a driving gear 15 which is provided with a hand crank, the said hand crank being fast on a shaft 17 which has bearings in the standard 2 and also has a bearing in a bracket 18 which depends from a boxing 21 on the arm 3. A bevel gear 19 is splined on the shaft 17 for rotation therewith and for longitudinal adjustment thereon, a set screw 20 being provided to secure the said beveled gear at any desired adjustment on the shaft.

The boxing 21 is mounted on the arm 3 for longitudinal adjustment thereon and has a bearing 22 for a vertical shaft 23. At the lower end of the shaft 23 is a large beveled gear wheel 24 which is engaged by the beveled gear or pinion 19. A lower cushioning spring 25 is arranged on the shaft 23 at a point above the bearing 22 and supports a washer 26 which is adapted to bear against the under side of a disk A arranged on the shaft for grinding.

A spring 27 is arranged on the upper portion of the shaft 23 and bears on the upper concaved face of the disk and is held in place by a nut 28 screwed on the threaded upper portion of the shaft. The springs 25—27 while serving to hold the disk at the correct elevation for grinding by the stone or disk 10 permit of slight vertical movement of said disk as is required while grinding the same. A post 29 projects upwardly from the cross bar 4 and is provided with a bracket 30 which is vertically adjustable thereon and may be secured at any desired adjustment by a set screw 31.

A substantially U-shaped arm 32 has the upper ends of its members pivotally connected to the bracket 30 as at 33 for vertical angular adjustment, the said arm 32 carrying a roller 34 which is adapted to bear on the upper side of the harrow disk at a point above the grind stone or disk 10.

It will be understood that when the shaft 17 is rotated by the crank 16, the train of gears hereinbefore described causes the grinding disk or stone 10 to be revolved and to sharpen the edge of the harrow disk and

it will also be understood that the gears 20—24 cause the shaft 23 which carries the harrow disk to be also slowly rotated so that all portions of the edge of the harrow disk 5 are successively presented to the grinding action of the stone or disk 10.

While I have herein shown and described a preferred form of my invention, I would have it understood that changes may be 10 made in the form, proportion and construction of the several parts without departing from the spirit of my invention and within the scope of the appended claims.

I claim:—

- 15 1. The herein described disk sharpener comprising a supporting standard, an arm extending horizontally from the standard, a boxing mounted for longitudinal movement on said arm, a vertical work revolving shaft 20 mounted in a bearing in said boxing and having a beveled gear at its lower end, a driving shaft mounted in bearings in the standard and in a bearing with which the boxing is provided, said shaft being parallel 25 with said arm and having an adjustable beveled pinion engaging said beveled gear, a revolute grinding element, a support and a

bearing therefor, connections between the driving shaft and grinding element to rotate the latter, a vertical post extending from the 30 upper end of the standard, a bracket adjustable on said post, an arm pivotally connected to said bracket and a roller mounted in said arm and arranged to engage the work at a point above the grinding element. 35

2. In a disk sharpener of the class described, the combination of a support, a driving shaft mounted in the support, a grinding element, connections between the driving shaft and grinding element to rotate the latter, a work carrying shaft arranged at an angle to the driving shaft and geared thereto, a roller arranged to engage the work at a point above the grinding element, a support for the said roller, and cushioning springs on the work carrying shaft to engage the upper and lower sides of the work. 40 45

In testimony whereof I affix my signature in presence of two witnesses.

JOHN D. STEWART.
